UNITED STATES PATENT OFFICE

162,546

SMOKER'S STAND

Leo Jiranek, New York, N. Y., assignor to Smokado Manufacturing Co., Inc., Bloomfield, N. J., a corporation of Delaware

Application August 31, 1950, Serial No. 12,006

Term of patent 14 years

(Cl. D85—2)

To all whom it may concern:

Be it known that I, Leo Jiranek, a citizen of the United States, residing at New York, in the county of New York and State of New York, have invented a new, original, and ornamental Design for a Smoker's Stand, of which the following is a specification, reference being had to the accompanying drawing, forming part thereof, in which

The sole figure is a perspective view of a smoker's stand, showing my new design.

I claim:

The ornamental design for a smoker's stand, substantially as shown.

LEO JIRANEK.
